UNITED STATES PATENT OFFICE.

JAMES J. MALLEY, OF ST. LOUIS, MISSOURI, ASSIGNOR OF ONE-HALF TO
HENRY J. BRINKENKAMP, OF SAME PLACE.

RANGE-TANK.

SPECIFICATION forming part of Letters Patent No. 530,700, dated December 11, 1894.

Application filed April 16, 1894. Serial No. 507,682. (No model.)

To all whom it may concern:

Be it known that I, JAMES J. MALLEY, of the city of St. Louis, State of Missouri, have invented certain new and useful Improvements 5 in Range-Tanks, of which the following is a full, clear, and exact description, reference being had to the accompanying drawings, forming a part hereof.

The object of this invention is to provide an 10 improved range tank formed of sheet metal.

My invention consists in the construction, arrangement, and combination of elements hereinafter set forth, pointed out in my claim, and illustrated by the accompanying drawings, in which—

Figure 1 is a plan view of the blank from which the cover of the tank is formed. Fig. 2 illustrates the tank cover after it is bent into shape for attachment to the body. Fig. 20 3 is a perspective view of the body portion of the tank. Fig. 4 is an enlarged transverse sectional view of the tank in process of construction. Fig. 5 is a plan view, showing the tank applied to a range. Fig. 6 is a perspective view of one end portion of the completed tank. Figs. 7, 8 and 9 are detail views of a tank corner in different stages of construction.

In the construction of the device as shown, the numeral 10 designates a receptacle, the 30 sides of which are formed of sheet metal.

The lower edges of the sides of the receptacle 10 are bent inwardly and upwardly (Fig. 4) and caused to embrace downwardly and inwardly curved portions 11 of the bottom 35 12 of the receptacle, which said portions are joined and hermetically sealed.

The upper edges of the side portions of the receptacle 10 are first bent outward, thus forming flanges 13, 14, the corners being cut 40 away, as shown in Fig. 3.

The cover 15 of the receptacle is formed of a sheet of metal 16, having notches 17 in the corners thereof, the side portions of the sheet 16 being bent down and inward on 45 the lines 18—18, as shown in Figs. 1 and 2 to form grooves to receive the margins of the flanges on the receptacle 10. The cover 15 is then slid longitudinally to proper position upon the flanges 13, 14, the latter sliding 50 loosely in the grooves of said cover and the

down turned edges 19 of said cover are then compressed against the edges of said flanges, as shown in Fig. 4, and illustrated in detail in Fig. 7.

The cover 15 has a lid aperture 20 therein, 55 near one end thereof, and diagonal cuts 21 are made in the metal at the corners of the said aperture, the said metal at the sides of said aperture being bent downwardly and forming flanges 22. Parallel to the cover 15, and 60 hinged thereto by means of hinges 23, 23, is a lid 24, which lid has down-turned outer edges forming flanges 25, 25, adapted to engage and confine flanges 26, 26 formed on, and horizontally extending from, the frame 65 27, also made of sheet metal and positioned in the aperture 20. A clip 28 is formed on, or fixed to, the end portion of the lid 24, opposite to the hinges 23, and extends upwardly and outwardly from said lid. After the cover 70 has been placed as above described the flanges 27, 29, 30, thus forming a projection horizontally and obliquely outside the plane of the side portions of the receptacle 10. The completed device illustrates 75 this down turned and outwardly extending projecting feature, as do also Figs. 8 and 9.

The completed device is adapted to be mounted adjacent to, or fixed upon, a range 80 by any desired connection, as illustrated in Fig. 5, the connections between the tank and range forming no part of my invention. In the construction of my improved tank, the cover 15 is not applied to the tank until after 85 it is known what is the relative position of the tank and range to which it is applied, thus providing for the positioning of the covers, relative to the tank, in accordance with the manner of attaching the tank to the range. 90 In other words, if the tank is to be what is known as a "left-hand" tank (applied to the left-hand end of the range), the cover should be turned about with relation to the tank until the end nearest which the lid-opening 95 is located is at the front end of the tank (or in other words outward), as it is always essential that the lid be located most convenient to the cook or other user, which is at the outer or front end of the tank. The construc- 100

tion above described is such that the cover may be slid into place on the tank from either end of the latter.

What I claim is—

- 5 The improved range-tank, comprising the body 10 having a closed bottom and substantially vertical side and end walls the upper edges of which are first bent outward to about a right-angle to form wide horizontal flanges 13, 14 which are cut away at each corner of said body to form an angular space thereat, the cover 15 formed of a sheet of metal and having an angular-notch 17 in each corner thereof, the edges of the cover-sheet being 10 bent down and inward to form grooves or channels which are engaged to the marginal-edges of said flanges 13, 14 on said body and compressed against the same, and the

20 said flanges 13, 14 of the body and the seamed margin of said cover being then conjunctively bent downward at a point some distance from the upright walls of said body to form a projection both horizontally and obliquely outside the plane of the side-portions of said body, and presenting a substantial and finished appearance, and said cover having an aperture to afford access to the interior of said body, and a lid applied to said aperture, substantially as herein specified.

25 In testimony whereof I affix my signature in presence of two witnesses.

JAMES J. MALLEY.
